DESIGN FOR A BRASSIÈRE

Elizabeth B. Haines Fisher, Mount Pleasant,
Mich.

Application November 6, 1937, Serial No. 72,660

Term of patent 14 years

To all whom it may concern:

Be it known that I, Elizabeth B. Haines Fisher, a citizen of the United States, residing at Mount Pleasant, in the county of Isabella and State of Michigan, have invented a new, original, and ornamental Design for a Brassière, of which the following is a specification, reference being had to the accompanying drawing, forming part thereof.

I claim:—

The ornamental design for a brassière, as shown.

ELIZABETH B. HAINES FISHER.
